Primary Examiner — Janice Hallmark*(74) Attorney, Agent, or Firm* — Anova Law Group, PLLC(57) **CLAIM**

The ornamental design for a fan, as shown and described.

DESCRIPTION

FIG. 1 is a front elevation view of a fan in accordance with the present disclosure;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof.

The broken lines represent unclaimed features of the fan that form no part of the claimed design.

1 Claim, 5 Drawing Sheets(56)
